UNITED STATES PATENT OFFICE.

JOSEPH ROSENBLATT, OF PROVIDENCE, RHODE ISLAND.

EYEGLASS-MOUNTING.

1,279,007.

Specification of Letters Patent. Patented Sept. 17, 1918.

Application filed December 19, 1916. Serial No. 137,769.

To all whom it may concern:

Be it known that I, JOSEPH ROSENBLATT, a citizen of the United States, and resident of the city of Providence, in the county of Providence and State of Rhode Island, have invented certain new and useful Improvements in Eyeglass-Mountings, of which the following is a specification.

This invention relates to eyeglass mountings more particularly to the frameless type of eyeglasses and spectacles, and the object of this invention is to provide a mounting with resilient means for engaging the edge of the lens at a point substantially on its horizontal axis with a yielding pressure, to obtain the following advantages; First, by my improved construction the axis of the lens is retained in its normal position irrespective of any looseness which may occur in its securing means; second, by the exerting of this yielding pressure upon the lens, it is always moved back to its normal position even when pressed therefrom in the course of handling; third, by retaining this lens in position by spring pressure the stud, rivet or screw which secures the lens to the ears may be left comparatively loose and the spring will compensate for uneven expansion of the different parts due to varying temperatures, thereby materially reducing the breakage of lenses.

With these and other objects in view, the invention consists of certain novel features of construction, as will be more fully described, and particularly pointed out in the appended claims.

In the accompanying drawings:

Figure 1— is a side elevation showing a portion of a lens retained in a lens clip and one form of my improved spring retaining arm engaging a rounding recess in the edge of the lens to hold it in position in the clip.

Fig. 2— is a view similar to Fig. 1 but wherein the end portion of the spring arm engages a V-shaped notch in the lens.

Fig. 3— shows the end of the spring arm as turned directly outward to engage the notch in the lens formed to receive it.

Fig. 4— is a sectional edge view of the lens as retained between two side ears, the spring arm being in section.

Fig. 5— is a sectional edge view showing the lens retained in a clip having but one side ear.

Fig. 6— is a perspective view showing the

clip of my improved form with a portion of a lens mounted therein.

Referring to the drawings, 10 designates the nose bridge member which joins the two lens straps or clips 11. Some of these clips are provided with a pair of side ears 12 as illustrated in Fig. 4 between which the lens 13 is mounted, while other clips may be provided with but a single ear as illustrated in Fig. 5, whereby it is better adapted to receive lenses of different thicknesses.

The heel portion 14 of this clip to which the bridge portion 10 is attached is provided with an arm 15 extending at substantially a right angle to the horizontal axis through the lens. This arm is bent over at 16 substantially upon itself and its end portion is provided with a protuberance or outwardly extending portion as at 17 which is adapted to engage a correspondingly shaped recess 18 in the edge of the lens.

This recess in the lens is preferably formed substantially on its major or horizontal axis, whereby this spring arm exerts a spring tension or pressure against the screw 19 or other member which secures the lens to the ear or ears.

In some instances, I form the notch 18 rounding as illustrated in Fig. 1; in other instances this notch may be made in a V-shape as at 20 in Fig. 2; or as illustrated at 21 in Fig. 3 the notch may be rectangular in shape, or the notch and its engaging portion on the arm may be made in any suitable or convenient shape for receiving and yieldably retaining the end of the arm therein.

In some instances as illustrated in Figs. 2 and 3, I provide a pad 22 such as felt, cork or the like on the engaging surface of this spring arm thereby providing a yielding surface which prevents direct contact of the metal of the arm with the glass of the lens, whereby breakage to some extent is prevented.

By this construction whereby the edge of the lens is engaged substantially on its horizontal axis by a yielding pressure, it will be observed that the usual saddle portion of the clip for engaging the edge of the lens both above and below the axial line of the lens may be omitted if desired and the lens is held entirely by the flexible or yieldable pressure of this spring arm, thereby providing means which perform the function of a shock absorbing device, materially reducing

the breakage of lenses in these mountings even when the same is dropped upon the floor. Then again by this construction the lens may be loosely secured to the clip ears, 5 in which case the action of this spring arm will always serve to bring the lens to its normal or correct position, even when moved therefrom by rough handling.

I have shown this spring arm 15 as extending first up and then downward and back to the axial center of the lens, but this arm may extend first downwardly if desired and then back to engage the edge of the lens.

I have described the spring arm as engaging 15 the notch in the edge of the lens substantially on its horizontal axis, but I do not wish to be restricted to this particular position of the notch, as this notch may be made in any convenient place along the edge of 20 the lens and engaged by a corresponding protuberance on a flexible arm.

In Fig. 3, I have also illustrated a downwardly extending spring arm 23 to engage the edge of the lens with a yielding pressure, which arm may be employed in addition to the arm engaging the notch if desired.

Another essential advantage of my spring 30 arm mounting is that the lens may be mounted therein without necessitating the extreme care in placing the lens in position usually required in the ordinary clip. In other words mechanics with much less skill may be employed than is necessary with the 35 other style of mounting which possesses the rigid form of saddle arms, as my yieldable arm will compensate for any inaccuracies which may occur in workmanship.

By the "heel of the clip" I mean that portion 40 where the ears 12 are connected together.

Having thus described an illustrative embodiment of my invention I desire it to be understood that although specific terms are 45 employed they are used in a generic and descriptive sense and not for the purpose of limitation, it being understood that I reserve the privilege of resorting to all mechanical changes to which the device is

clearly susceptible, the scope of the invention being defined by the appended claims.

I claim:

1. An eyeglass mounting comprising a clip having an attaching ear in which the lens is designed to be mounted, a resilient arm at the heel of the clip extending therefrom along the edge of the lens and having a portion folded back upon itself, and means in said arm for engaging a recess in the lens with a yielding pressure.

2. An eyeglass mounting comprising a clip having a lens-supporting ear, a resilient arm at the heel of the clip extending therefrom at substantially a right angle to the longitudinal axis of the supporting ear, 65 said arm being folded back upon itself and provided with a protuberance near its end for engaging a recess in the edge of the lens with a yielding pressure.

3. An eyeglass mounting comprising a 70 clip having an attaching ear in which the lens is designed to be pivotally mounted, a resilient arm at the heel of the clip extending therefrom at substantially a right angle to the longitudinal axis of the attaching ear, 75 said arm being folded back upon itself, a protuberance on said arm near its end for engaging a recess in the edge of the lens with a yielding pressure, the lens-engaging portion of said arm being provided with a 80 cushion of soft material.

4. An eyeglass mounting comprising a clip having a lens-supporting member, a 85 pair of arms at the heel of the clip extending in opposite directions at substantially right angles to the longitudinal axis through said supporting members, one of said arms being folded upon itself to engage the edge of the lens substantially at its center line, and the other of said arms extending along 90 the edge of the lens to engage it at a point remote from its center lines.

In testimony whereof I affix my signature in presence of a witness.

JOSEPH ROSENBLATT.
